UNITED STATES PATENT OFFICE.

ROBERT J. SHEEHY, OF NEW YORK, N. Y.

DYNAMO-ELECTRIC MACHINE.

SPECIFICATION forming part of Letters Patent No. 285,691, dated September 25, 1882.

Application filed November 22, 1882. (No model.)

To all whom it may concern:

Be it known that I, ROBERT J. SHEEHY, a citizen of the United States, residing in the city, county, and State of New York, have invented certain new and useful Improvements in Dynamo-Electric Machines, of which the following is a specification.

My invention relates to the art and practice of economically converting mechanical into electrical energy.

It has for its object to increase the efficiency of the so-called "dynamo-electric machine," especially such forms as are employed in the production of currents of large volume and high intensity. It concerns, in this connection, the methods of utilizing the magnetic field, of economically maintaining the magnetic intensity, of applying the power to rotate the armatures, of adapting the armature-conductors to the requirements of the external circuit, of maintaining a uniform current throughout any given circuit, and to other matters of less importance.

In general the more important improvements herein set forth may be described as follows: First, for the purpose of generating currents economically I have constructed my machine with a number of field pole-pieces, arranged in a series of alternating polarities, and have provided intermediate armatures between adjacent pole-pieces and exterior armatures against the outer faces of exterior pole-pieces; secondly, I maintain the fields of the several armatures by means of the currents generated in said outer armatures, employing one or both, as may be required; thirdly, I communicate the power from a main shaft to the independent armature-shafts through the medium of friction-gearings, which may be independently operated; fourthly, I provide mechanism whereby the length of the conductors in each of the several bobbins of any armature may be simultaneously increased or reduced to compensate for changes in the conditions of the external circuit; and, fifthly, I provide means for automatically operating said mechanism for varying the length of the conductors in the armature-bobbins when the normal strength of current is disturbed thereby, so altering the electro-motive force and internal resistance of said armature as to re-

store the normal strength of current generated.

My invention also includes certain other minor details of construction, the exact subject-matter claimed being hereinafter specifically designated.

In the accompanying drawings, Figure 1 is an elevation, and Fig. 2 a plan, of my compound dynamo-electric generator or bank of generators. Fig. 3 is a longitudinal view, partially in section, of one of the armatures, showing the commutator mechanism, the mechanism for varying the length of armature-conductors, and the motor for automatically actuating the same. Fig. 4 is a section, and Fig. 5 a face view, of the commutator employed in conjunction with each armature. Fig. 6 is an end view of the apparatus for varying the length of said armature-conductors. Fig. 7 is a modification of my improvements, consisting of a combination of a commutator with the mechanism for varying the length of armature-conductors; and Fig. 8 is a detached view of one of the cores of the armature-bobbins.

Similar letters of reference are applied in the several figures to the same parts.

Referring to the drawings, A' A² represent two electro-magnets, with yokes B' and B² respectively. The pole-pieces of these electro-magnets are shown at C', C², C³, and C⁴, respectively. Each of the pole-pieces C consists of a block of iron having a longitudinal semicircular recess, e, formed in each side thereof. The helices of the electro-magnets are connected together in one electric circuit, the winding being in such directions that under the influence of the current the polarization of the alternate pole-pieces will be opposite. Thus, for example, that of C' will be north, that of C² south, &c.

Within each of the cylindrical openings formed by the confronting recesses e, made in the extensions C', C², C³, and C⁴, as also within each of the recesses formed in the outer surfaces of the two extreme pole-pieces C' and C⁴, is placed a cylindrical armature, D. The outer armatures, D' and D², are each provided with a field of force created by the pole-piece C upon one side only, whereas the three intermediate armatures D², D³, and D⁴ are each provided with fields of force created by a pole-

piece upon each side. The former therefore revolve in a field of one polarity, while the latter revolve through two fields of opposite polarity.

5 Against the extremities of each pole-piece C is secured an iron plate, E, which serves to extend the magnetic field over the ends of the armature-bobbins as they are revolved in proximity to that extension. A standard, F, preferably of non-magnetic metal, is secured to each of the plates E, at the ends of each armature, and within said standards are formed suitable journal-boxes, f, for receiving the respective ends of the armature-shaft d.

15 The armatures D are independently connected through their shafts d with a horizontal shaft, G, extending in a direction at right angles therewith. The horizontal shaft G carries a pulley, g, by means of which a rotary motion may be communicated thereto from any suitable source of power. The rotary movement of the shaft G is communicated to the armatures D, respectively, by means of bevelled friction-wheels H and I, of compressed 20 paper, mounted upon the shaft G and the individual armature-shafts d. I prefer, also, to so construct the friction-wheels H that they may be independently disengaged from their respective armature-wheels I at will. This I 25 accomplish by connecting each of the wheels H to the shaft G by a convenient spline-and-feather attachment, which permits a horizontal movement of the same to and from the friction-wheels I. In the sleeve h' of each of the 30 friction-wheels H is formed an annular groove, h'', for receiving the two semicircular prongs j j of a forked lever, J. The levers J are each pivoted at a point, j', in a manner allowing the extremities of the prongs j j to be moved longitudinally along the shaft G, carrying therewith the friction-wheel H. At the remote extremity of each lever J is formed a slot, k, for receiving a pin, k', carried upon a cam-lever, K. By means of this system any desired number 35 of armatures may be actuated.

40 The construction of the armature which I prefer to employ in this connection consists of an annular series of coils, L' to L⁸, of insulated wire, surrounding the armature-shaft d. Each of the coils L is constructed with a hollow rectangular core, M, of soft iron, and these cores are, for convenience, constructed of four sections, m', m², m³, and m⁴. The sections m are constructed to fit together in the manner 45 shown in Fig. 8, with their edges projecting slightly beyond the opposite sides of the coils, and forming tenons n, which fit into corresponding apertures, n', formed in a series of horizontal girders, N. The girders N are supported at their respective extremities by means of two soft-iron cylinder-heads, O and O', affixed to the armature-shaft d in the manner described in an application for Letters Patent filed by me November 7, 1882. Suitable radial lugs, o, are formed upon the inner surface 55 of each cylinder-head O and O', to which the

girders N are bolted. For the purpose of surrounding the coils L to as great an extent as possible with inductive metal, I place a plate, P, of soft iron, longitudinally beneath each coil 70 L, and support it at either end in grooves o' o' also formed in the inner face of the heads O, and O'. A sufficient space is preferably left between the surfaces of the coils L, adjacent to the heads O and O', as also between the coils 75 and the longitudinal plates P, to allow a free circulation of air for the purpose of cooling the machine.

80 The inner terminal of each coil L of each armature is connected with the inner terminal of the diametrically-opposite coil, in a manner to be hereinafter described. The outer terminal of each coil is connected with an individual segment r' r'' to r⁴ r²⁴ of a commutator, R, carried at one end of each armature-shaft d 85 and revolving therewith. The commutators R each consists of a metallic disk, S, secured to the armature shaft d, and faced upon one side with compressed paper or other suitable insulating material, as shown at s. The curved 90 segments r' r'', &c., are secured to the iron supporting disk S by suitable studs, s², which serve to separate the segments from the disk and allow air to circulate between the two, and prevent false connections from being established between adjacent plates through the accumulation of metallic dust from the commutator. The segments r' r'', &c., are thus arranged upon the lateral face of the commutator, and forming rings concentric with the 95 axis of the shaft d, as shown in Fig. 5. In each ring there are two segments placed diametrically opposite each other, and the spaces intervening between the adjacent ends are occupied by projections s³, of non-conducting 100 material, extending from the disk. The complete rings thus formed are relatively so arranged that the insulating-segments s³ succeed each other at regular angular distances.

105 In the drawings I have shown the commutator with four complete rings, comprising eight sections, corresponding to the eight coils L' to L⁸ of wire in the armature, with which they are respectively connected. The position of the commutator with reference to the 110 polar extensions C is such that during the period in its revolution when a current of a given direction is being generated in any given inductive coil—as, for example, L' of the armature—the outer terminal of that coil will be 115 connected through its commutator-segment r' with one of the collecting-brushes T'. The inner terminal, as before mentioned, is connected with the inner terminal of the diametrically-opposite coil, L⁵, and the outer terminal 120 of the latter to the diametrically-opposite segment, r'', of the commutator and collecting-brush T². At the moment, however, that the current ceases to be generated in the coils L' and L⁸, or becomes too weak to be of service, 125 the connections with the brushes T' and T² are severed by the intervention of the non-con-

ducting segments s^3 . At the instant, or immediately before, the connections of any given coil are severed, the connections of the next succeeding coil are completed with the same 5 contact-brushes. The current is thus at all times collected from a constant amount of inductive wire. The commutator-brushes T' and T^2 are supported at the respective extremities of an arm, s^4 , which is supported at its 10 center upon a collar, s^5 , surrounding the shaft d , and constituting a journal in which the arm may be rocked. A clamp, s^6 , is fastened to, but insulated from, each extremity of the arm s^4 , and in these clamps the contact-brushes are 15 held in their required positions by means of set-screws s^7 . The angular position of the arm may be manually adjusted, as required, for the purpose of bringing the brushes in the proper positions relative to the commutator- 20 segments.

For the purpose of preventing the occurrence of electric discharges or sparks between the brushes T' and T^2 and the successive commutator-segments when the circuit between 25 the same is interrupted, I employ a series of contact-segments, t' to t^8 , and independent contact-brushes T^3 and T^4 , for short-circuiting the successive coils immediately before or at the instant their connections with the brushes T' 30 and T^2 are severed. The segments t' to t^8 are preferably arranged in an annular series at the back of the disk S , and are supported by lugs extending therefrom. The outer terminal of the armature-coil L' is connected with 35 the segment t' , the corresponding terminal of coil L^2 with segment t^2 , and so on in regular succession.

The two contact-brushes T^3 and T^4 are respectively carried in brackets forming extensions 40 of the clamps s^6 . These brushes are in direct electrical connection with each other through a conductor, 1, and a resistance-coil, T^8 , may be included for the purpose of diminishing the strength of current traversing said conductor. The positions of the respective segment t and segment r , to which any given terminal is connected, are so arranged relatively to their respective contact-brushes that immediately upon or before the segment r passes 45 from beneath the brush T' or T^2 the corresponding segment, t , will be brought into contact with the brush T^3 or T^4 . The force of the residual current in the armature-coil will thereupon be expended in the circuit of the 50 conductor 1.

For the purpose of regulating the volume or strength of the current generated in each armature independently of the remainder, I construct the coils of each armature in such a 55 manner that a greater or less portion of the wire constituting the same may be employed at will, thus varying the total amount of active inductive wire in the circuit. The means whereby I accomplish this end consists in placing upon each armature-shaft d , at the end 60 of the armature D , away from the commutator

R , a disk, U , of non-conducting material—such, for example, as compressed paper—carried upon the face of a metallic supporting-plate, U^2 , and in mounting thereon eight radial series of contact-points, u . Any requisite number of individual contact-points u may be contained in the radial series; but each series is preferably constructed with the same number, and the consecutive contact-points are arranged at equidistant intervals from each other, and the inner ones of all the series the same distance from the center of the disk U . The successive contact-points u are electrically connected by conductors u^2 with the successive 70 layers or groups of layers of the insulated wire constituting the bobbins L of the armature D . Thus, beginning at the center of the bobbin, the inner contact-point, u , of any given radial series is connected with the inner group of convolutions of that armature-bobbin which is in the same axial plane therewith, the second contact-point from the center is connected with a second group of convolutions in the same armature-bobbin, the 75 third contact-point likewise with a third group, and so on. The same construction is followed out with reference to each bobbin and its radial series of contact-points.

For the purpose of automatically determining the amount of wire which shall be rendered operative at any given time, and thus controlling the strength of the current transmitted to the external circuit, I have devised the following means for simultaneously placing 80 any of the contact-points u in all the series in electrical connection with the corresponding contact-point of the diametrically-opposite series, and determining which set of contact-points shall thus be connected by means of the 85 strength of the current in the external circuit. An electro-magnetic motor, V , of any suitable construction, is included in the external circuit of each armature of the generator, and arranged to revolve a shaft, v , in the direction 90 indicated by the arrow, under the influence of an electric current of increasing strength, and to allow the same to be revolved in the opposite direction through the influence of a weight, v' , when the current traversing the coils of the 95 motor decreases in strength.

Upon the shaft v is formed a continuous thread, along which a corresponding threaded traveler, v^2 , is caused to move in one direction or the other, according to the direction 100 of revolution of the shaft. The two prongs w of a forked lever, W , extend upon opposite sides of the traveler v^2 , and are loosely jointed thereto by means of the transverse studs w^3 , projecting from the traveler through 105 elongated slots w^4 , formed in the extremities of the respective prongs. The lever W is pivoted at a point, w^5 , and is forked at the extremity remote from the shaft v in a manner similar to that described with reference to the 110 lever J , as shown at $w^6 w^7$. The prongs w^8 and w^9 embrace a collar, X , surrounding the armature D .

ture-shaft d , and longitudinally movable upon a feather, x . An annular groove, x' , is formed at one end of the collar X , into which groove the extremities of the fork-prongs $w^i w^i$ extend. 5 This construction permits the collar to revolve with the shaft d , and at the same time affords a permanent lateral connection with the lever W . The extremity of the collar X remote from the groove x' engages the short arms of 10 a series of eight levers, Y , which serve to close the circuits between the diametrically-opposite contact-points u , in a manner hereinafter described. The levers Y are respectively pivoted at points equidistant from each other to 15 annular lugs y , formed upon a collar, y' , which collar surrounds the shaft and is rigidly attached thereto. Each of the levers is, moreover, so constructed that the extremity of its long arm y^i , which is preferably insulated from 20 the lever itself by an intervening block, y^i , of compressed paper or other suitable insulating material, may be swung outward from the center of the shaft d in the plane of the radial series of contact-points u , to which it corresponds. 25

Directly in front of each radial series of contact-points u , and extending parallel thereto, is a guide-rail, u' , supported at each end from the disk U by arms u^i , extending through the 30 metallic supporting-plate U^i , but insulated therefrom. Each guide-rail u' is provided with a movable collar or traveler, u^i , upon which is carried a circuit-closer, u^i , hereinafter described. A slot, y^i , is formed in the extremity 35 of each arm y^i of the levers Y , through which slot extends a stud, u^i , formed upon each of the travelers u^i . The circuit-closers U' each consists of a wheel, u^i , having four teeth or 40 projections, two of which, diametrically opposite each other, are of slate or other suitable non-conducting and non-inflammable material. This four-armed wheel is pivoted at its center to a resilient arm, u^i , of conducting material, rigidly supported from and in electrical 45 connection with the carrier u^i . The conducting teeth or prongs of the wheel u^i have their extremities rounded, and are constructed to fit into recesses u^i , formed in the faces of each of the contact-points u . The insulating teeth 50 or prongs enter between adjacent contact-points, and serve to prevent an electric discharge from taking place between the adjacent points when the contact between one of the conducting-arms and one of said points is suddenly broken during the passage of the wheel. 55

It will now be evident that when the collar X is moved forward toward the lug y , to which the levers Y are pivoted, the short arms of the levers will be pressed outward, and the long 60 arms y^i forced toward the center of the shaft, thereby bringing the circuit-closers into contact with the inner contact-points, u . When, on the other hand, the collar X is moved in the opposite direction, the long arms of the levers will be carried outward by means of the 65 force exerted by the springs Y' , combined with

the centrifugal force occasioned by the rapid revolution of the armature-shaft. As the arms y^i are carried outward the circuit-closers U' make connections between the successive contact-points u and the guide-rails u' . The rails u' , which correspond with the diametrically-opposite armature-coils, are electrically connected with each other by conductors 2. The object of this regulating mechanism is to maintain a constant uniformity in the strength of current traversing the external circuit. 70 75

The operation of the device is as follows: As shown in the figure, the circuit-closers U' are in contact with the inner circular range of 80 contact-points u , which, as already described, are connected with the inner terminals of the innermost groups of conductors of the respective bobbins to which they correspond. This is the condition best suited to the development 85 of currents of high electro-motive force. If, now, for any reason the resistance of the external circuit is diminished, the strength of current in the circuit will be proportionally increased. This will operate the motor V to 90 withdraw the collar X and allow the outward movement of the levers Y . The circuit-closers U' , on leaving the inner circular series of contact-points u and making connections with the second series, eliminate from the main circuit 95 the inner group of conductors, as already explained. This simultaneously reduces the electro-motive force of the current generated and the internal resistance of the machine. If the strength of current is still excessive, the 100 circuit-closers are still farther advanced, and the length of wire in the armature still farther decreased. Ultimately the condition is reached in which the original strength of current is again established throughout the circuit. On 105 the other hand, if the strength of the current generated falls below the predetermined point, the motor-shaft v is rotated in the opposite direction by means of the weight v' and the convolutions are reintroduced. 110

For the purpose of adjusting the motor to respond to currents of any required strength, I prefer to attach the cord supporting the weight to a conical drum, Z , in such a manner that the weight will exert a greater retarding influence upon the shaft v at the start than thereafter, to prevent action of the regulator in response to slight diminutions of resistance or variations of speed of the machine. 115

It is desirable that the time intervening between the breaking of the circuit with one contact-point u and the closing of the circuit with the next succeeding point should be as small as possible. For the purpose of effecting this result, and to prevent the circuit-closers from remaining at positions intermediate between two contact-points u , I mount upon the shaft v an arm, z , carrying at its extremity a pyramidal wedge, z' , and place in the path of its revolution an adjustable tension-clutch, z'' , consisting of two resilient arms or springs, z'' , normally so far separated as to allow the 120 125 130

cam z' to enter the space between them, but not to allow it to pass between without separating them still farther. This renders the movement intermittent.

5 The respective parts of the machine are so adjusted that one revolution of the shaft v will cause the circuit-closer U' to be moved from one contact-point u into contact with the succeeding point. The resilience of the springs z^2 will be sufficient to normally hold the pyramidal wedge z' and prevent the operation of the motor. When, however, the current increases sufficiently to force the wedge through the springs, the shaft will immediately complete one entire revolution and the circuit will be completed through the succeeding contact-point u . This operation is repeated with every increase in the strength of the current which is adequate to effect the operation. For 10 the purpose of allowing the shaft v to be revolved freely in the reverse direction, I prefer to mount the springs z^2 upon a hinged support, z^4 , which is normally held in an upright position by the spring z^5 , but which will be 15 thrown backward and temporarily carry the springs out of the path of the wedge z' when the latter strikes the springs upon the opposite side.

In Fig. 7 I have shown a modification in the 20 construction of the device employed for cutting the successive layers of bobbin-wire out of circuit. The object of this modification is to combine a commutator with the device for varying the length of the armature-conductors; 25 and thereby dispense with the commutator placed at the opposite extremity of the armatures. It consists in constituting each lever Y a conductor, and pivoting them in a non-conducting support. An annular series of metallic contact-segments, t^6 to t^{16} , surrounds the levers Y , one of which is adjacent to and in 30 electrical connection with each of said segments. The brushes T^6 and T^{16} will then at any time be in electrical connection with the 35 outer terminals of opposite bobbins. Assuming that the inner terminals are connected together directly, and that the connections between opposite guide-arms have in this instance been severed, currents will be collected 40 by said brushes, which will depend in strength upon the positions of the circuit-closers U' . This combined collector and governor may be advantageously employed in conjunction with 45 many of the well-known forms of machine.

50 The bank of generators thus described may be regarded as a collection of separate generators, or as a single instrument, and the individual armatures may be operated in series—multiple arc—or may be independently employed on separate circuits.

I am aware that the coils or convolutions of field-magnet helices have been introduced into and withdrawn from the circuit of a dynamo-electric generator for the purpose of varying 55 the intensity of the field of force, and thereby indirectly modifying the strength of current

generated; but the plan of regulation presented herein is essentially different from this, inasmuch as it aims to directly modify the intensity of the current generated by varying the length of wire subject to inductive action in the bobbins of the armature.

I claim as my invention—

1. The combination, substantially as herein-before set forth, of an electro-magnet, its pole-pieces, an armature moving within the field of magnetic force created between the inner faces of said pole-pieces, and independent armatures moving within the exterior field or fields created by the outer faces of said pole-pieces. 75

2. The combination, substantially as herein-before set forth, of two or more electro-magnets, four or more pole-pieces thereof arranged consecutively with alternating polarities, armatures moved within the field of magnetic 85 force created between the confronting faces of the pole-pieces of the same or of adjacent electro-magnets, and armatures moved within the fields created by the external faces of the outermost pole-pieces. 90

3. The combination, substantially as herein-before set forth, of two or more electro-magnets, their pole-pieces arranged consecutively with alternating polarities, armatures moved within the intermediate fields between adjacent pole-pieces, armatures moved within the exterior fields created by the outer faces of said pole-pieces, and a magnetizing-circuit 95 the current within which is supplied by one or both of the armatures moving within said exterior fields for maintaining the fields of all of said armatures. 100

4. In combination with the armatures of a battery of dynamo-electric machines, a shaft for each armature, a friction-wheel on each armature-shaft, an independent driving-shaft, and mechanism for independently engaging the friction-wheels on the independent shaft with those on the armature-shafts. 105

5. In combination with the armatures of a battery of two or more dynamo-electric machines, two or more separate armature-shafts, friction-wheels mounted on said armature-shafts, an independent shaft, friction-wheels on said independent shaft, a forked lever for independently sliding each of said friction-wheels on said independent shaft, and a cam-lever for locking said friction-wheels upon 110 said independent shaft into and out of engagement with the friction-wheels on the armature-shafts respectively. 115

6. The combination, substantially as herein-before set forth, of an armature-bobbin, a conductor disposed thereupon in several convolutions or layers of evolutions, a series of contact-points respectively connected with the terminals of each of said convolutions or layers of convolutions, and an automatic traveling circuit-closer making contact with said contact-points, for the purpose of introducing 125 one or more of said convolutions or layers of convolutions into a circuit of conductors. 130

7. The combination, substantially as hereinbefore set forth, of two bobbins carried on either side of a central shaft, a radial series of contact-points for each bobbin respectively connected to the conductors of said bobbins at different points in their lengths, and traveling circuit-closers electrically connected together and simultaneously making contact with corresponding contact-points in the respective radial series for the purpose of connecting the conductors of one bobbin with those of the other, and for simultaneously and equally varying the length of the conductor in each. 70
8. The combination, substantially as hereinbefore set forth, of an annular series of bobbins, a commutator provided with conducting-segments corresponding to said bobbins and in electrical connection respectively with their outer terminals, a radial series of contact-points for each bobbin, said contact-points being respectively connected with each of the conductors of said bobbins at corresponding points throughout their lengths, and traveling circuit-closers for connecting diametrically opposite bobbins through corresponding contact-points. 80
9. The combination, substantially as hereinbefore set forth, of an annular series of bobbins, a radial series of contact-points for each bobbin, the contact-points of each series being respectively connected with the conductors of said bobbins at corresponding points in their lengths, and traveling circuit-closers for connecting diametrically - opposite bobbins through the medium of said contact-points. 85
10. The combination, substantially as hereinbefore set forth, of an annular series of bobbins, commutator-sections connected to the outer terminals of said bobbins, and means whereby the inner terminals or corresponding points along the lengths of the conductors constituting the diametrically-opposite bobbins may be connected together. 90
11. The combination, substantially as hereinbefore set forth, of an annular series of bobbins, a main line maintained in electrical connection with the outer terminals of said bobbins through commutator mechanism, and means whereby equal and corresponding fractions of the coils of such of said bobbins as are in action may be introduced into or withdrawn from said main line correlative with the changes in the strength of current traversing the same. 100
12. The combination, substantially as hereinbefore set forth, of an annular series of bobbins, mechanism for varying the lengths of the armature-conductors in action, and a motor whose movements are controlled by changes in the strength of current for actuating said mechanism. 110
13. The combination, substantially as hereinbefore set forth, of an annular series of bobbins, contact-points arranged in circular and radial series and revolving simultaneously with said bobbins, traveling circuit-closers for each of said radial series, and a motor operating under changes in the strength of current traversing the main line for simultaneously actuating all of said circuit-closers. 115
14. The combination, substantially as hereinbefore set forth, of an annular series of bobbins, a radial series of contact-points for each of said bobbins, traveling circuit-closers for each radial series, the diametrically-opposite circuit-closers being in electrical connection, a wedge-collar for simultaneously actuating said circuit-closers each to travel radially and make successive engagements with said contact-points, and a motor operating intermittently to actuate said collar. 120
15. The combination, substantially as hereinbefore set forth, of contact-points arranged in circular and radial series, circuit-closers traveling in the lines of said radial series, each consisting of a wheel provided with four teeth, two opposite teeth being of non-conducting and incombustible material for intervening between adjacent contact-points, thereby preventing sparks and consequent deterioration. 125
16. The combination, substantially as hereinbefore set forth, of mechanism for varying the length of the working-conductor in an armature-bobbin, a motor whose movements are controlled by variations in the strength of current generated in said working-conductor, and mechanism for rendering the action of said motor intermittent. 130
17. The combination, substantially as hereinbefore set forth, of mechanism for varying the length of working-conductors in two or more armature-bobbins, a motor whose movements are controlled by changes of strength in the current generated by said bobbins, and mechanism for rendering the action of said motor intermittent when said variation is caused by an increase. 135
18. The combination, substantially as hereinbefore set forth, of mechanism for varying the length of working-conductors in diametrically - opposite armature - bobbins, a motor whose movements are determined by increases in the strength of current generated in said bobbins to actuate said mechanism, to intermittently diminish the length of said conductors, but to increase them uniformly in accordance with said variation. 140
19. The combination, substantially as hereinbefore set forth, of mechanism for varying the length of active conductor upon an armature, a motor actuated by changes of strength of the current generated by said armature, a motor-shaft, a pyramidal wedge carried by said shaft, and mechanism for retarding the passage of said wedge in one direction only. 145
20. The combination, substantially as hereinbefore set forth, of an armature, a motor for varying the length of the active conductor upon said armature, a motor-shaft and pyramidal wedge carried by said shaft, springs permitting the passage of said wedge between them in one direction, but with retarding in-

fluence, and a shouldered lever carrying said springs, said lever being depressed by said wedge when moving in the opposite direction for the purpose of allowing its free passage.

5 21. The combination, substantially as hereinbefore set forth, of an armature generating electrical currents, a motor operating in opposition to a weight for controlling through intermediate mechanism the strength of current generated by said armature, a drum upon which the supporting-cord of said weight is

wound, having a part of its surface conical for increasing the leverage necessary to wind said weight for the purpose of opposing the action of the motor at certain times.

15 In testimony whereof I have hereunto subscribed my name this 21st day of November, A. D. 1882.

ROBERT J. SHEEHY.
